UNITED STATES PATENT OFFICE.

NEIL D. LENNER, OF AKRON, OHIO.

WASHBOARD.

Application filed September 19, 1922. Serial No. 589,066.

To all whom it may concern:

Be it known that I, NEIL D. LENNER, a citizen of the United States, residing at Akron, in the county of Summit and State 5 of Ohio, have invented certain new and useful Improvements in Washboards, of which the following is a specification.

The present invention relates to certain new and useful improvements in the construction of washboards of that general character which are provided with rubber rubbing surfaces, and the primary object of the invention is to provide an effective and inexpensive means for anchoring or securing 10 the rubber rubbing surface to the washboard frame in such a manner that there is no possibility of the rubbing surface becoming accidentally detached or displaced when the washboard is in use.

20 The idea of providing a washboard with a rubber rubbing surface is not broadly new, and while such a rubbing surface has many distinct advantages over the usual zinc or sheet metal rubbing surface, the difficulty in 25 anchoring the rubber rubbing surface to the frame without resorting to comparatively expensive expedients has made the manufacture of such washboards too costly for the rubber faced washboard to compete 30 commercially with the well known metal faced washboard. This difficulty is overcome by the present invention, which provides a simple, inexpensive and efficient means for securing a rubber rubbing surface 35 to the frame of a washboard.

It may be stated that a rubbing surface of some yieldable material, such as rubber, has been found to be very satisfactory and effective in washing clothes and fabrics. The 40 rubber presents a slightly yielding rubbing surface which tends to frictionally engage the fabric and to act upon the same in the necessary manner to loosen and remove the dirt without causing any unnecessary or 45 undue wear upon the fabric. A further advantage over the metal rubbing surface is that there is not the same possibility that a jagged edge may be unexpectedly presented at any time in such a manner as to tear the 50 fabric or mutilate the hands.

For a full understanding of the invention, reference is to be had to the following description and accompanying drawings, in which,

Figure 1 is a perspective view of a washboard constructed in accordance with the invention. 55

Figure 2 is an enlarged vertical sectional view through the soap rest and adjacent portions of the backboard and rubbing surface, showing the manner of anchoring the rubbing surface to the washboard frame. 60

Figure 3 is an enlarged perspective view of one of the metal clips which is utilized in securing the upper and lower edges of the 65 rubbing surface to the backboard portions of the supporting frame. 65

Figure 4 is a detached plan view of the upper portion of the rubbing surface and the corresponding ends of the backboards, 70 showing the manner of attaching the rubbing surface to the ends of the backboards. 70

Figure 5 is an enlarged vertical sectional view through the lower cross bar and adjacent portions of the backboard and rubbing 75 surface, showing the manner of anchoring the lower end of the rubbing surface to the washboard frame. 75

Corresponding and like parts are referred to in the following description and indicated 80 on all of the views of the drawings by like reference characters.

Referring to the drawings which illustrate one of many possible embodiments of the invention, the numerals 1 designate the side 85 bars of the washboard frame, said side bars being connected at their upper ends by the cross piece 2 and at a point spaced from their lower ends by the cross bar 3. The lower end portions 1^a of the side bars extend 90 downwardly below the cross bar 3 and provide the usual legs for supporting the washboard in position when it is in use. 90

The soap rest 4 connects the side bars 1 at an intermediate point, and a brand board 95 5 is fitted in position between the said soap rest and the upper cross bar 2, while the backboards 6 are fitted in position between the soap rest and the lower cross bar 3, thereby completing the supporting frame 100 for the rubbing surface. The upper edge of the soap rest 4 is provided with a groove 7 to receive the lower edge of the brand board 5, and the other edges of the brand board may be fitted in similar grooves in the upper 105 cross bar 2 and side bars 1, in a manner which is common and well known in the construction of washboards. The lower edge

of the soap rest 4 and upper edge of the lower cross bar 3 are grooved, as indicated at 8, to receive the reduced ends 6^a of the backboards 6 and the ends of the rubber rubbing surface 9. The side bars 1 are also provided upon their inner faces with the usual longitudinally extending grooves 10 which receive the vertical edge portions of the backboards and rubber rubbing surface 9. The upper and lower cross bars 2 and 3 and the soap rest 4 may be broadly referred to as the cross members of the frame. The rubbing surface is formed of some slightly yielding material, such as rubber, and the working surface thereof is suitably roughened. The manner of accomplishing this result is not material to the invention, and the roughened portion of the rubbing surface may be of any usual or suitable configuration, although for illustrative purposes the rubbing surface is shown as provided with a series of transversely extending ribs 9^a, which are substantially V shaped in cross section. The material for the rubbing surface can be produced in large sheets which are subsequently cut up into smaller parts of the appropriate size for use in the manufacture of these washboards. This in itself is a feature which greatly decreases the cost of manufacture, since it is much cheaper to produce the rubber rubbing surfaces in this manner than by molding or manufacturing the rubbing surfaces for the washboards individually, as is necessary where the edge portions of the rubbing surface have a flanged or special construction adapted for use in securing the rubbing surface to the washboard frame. The rubbing surface 9 is cut from a large sheet of material and is of the proper size to fit over the backboards 6, so that it will be substantially co-extensive with the front surface of the backboards, and the edge portions of the rubbing surface will be received within the grooves of the soap rest 4, lower cross bar 3 and side bars 1. Certain edge portions of the rubbing surface, in the present instance, the upper and lower edge portions thereof, are securely anchored to the corresponding edges of the backboards 6 by means of metal clips 11. These clips are preferably formed of some metal such as copper which will not readily rust or corrode, and they are shown as having a channel shaped formation, so that they are seated in the grooves of cross members of the frame and embrace the adjacent edges of the backboard and rubbing surface. The outside flange 11^a of each of the metal clips 11 is preferably given a curved or hooked formation, as indicated quite clearly by Figures 2 and 3, so that it will interlock with one of the ribs 9^a of the rubber rubbing surface and tend to firmly grip the rubber. The metal clip may be of any desired length and

either one metal clip or a series of the metal clips may be utilized, as desired. As indicated by Figure 4, the backboard is formed in three sections and there is one of the metal clips for each of the backboard sections. The metal clips can be readily applied to the rubbing surface and backboards of the supporting frame before the said elements are inserted in the side bars and cross members of the frame. After the washboard parts have been finally assembled, the clips 11 are firmly seated in the bases of the grooves 8 so that they are held securely in position thereby. When thus held in position the curved flanges 11^a of the metal clips either interlock with roughened portions such as the ribs 9^a of the rubbing surface or bite into and grip the rubbing surface so that the rubbing surface is permanently anchored in position. A simple and inexpensive means is thus provided for firmly fastening the rubber rubbing surface in position and there is no necessity of molding or forming the rubbing surfaces for the different washboards individually, as is necessary with those rubbing surfaces which have specially constructed edge portions.

The portion of the soap rest 4 which projects forwardly from the brand board is preferably constructed in such a way as to drain over the front of the rubbing surface. For this purpose I have shown the soap rest as provided at the top thereof with a longitudinally extending gutter 12, the base of the gutter communicating with drain openings 13 which extend parallel to the rubbing surface and discharge at the top of the rubbing surface.

While I have illustrated and described one particular embodiment of my washboard invention in detail, it will be understood that I do not restrict myself to the exact construction shown, since many modifications and changes are possible in the details of construction within the scope of the claims.

Having thus described my invention what I claim as new and desire to secure by Letters Patent is,

1. In a washboard, the combination with a frame and a rubber rubbing surface, of metal clips for securing the rubbing surface to the frame.
2. In a washboard, the combination with a frame and a rubber rubbing surface, of metal clips having jaw portions for engaging the rubber and other portions engaging the frame to anchor the rubbing surface to the frame.
3. In a washboard, the combination with a frame and a rubber rubbing surface, of channel shaped clips embracing edge portions of the rubber and portions of the frame for anchoring the rubbing surface to the frame.
4. In a washboard, the combination with

- a frame and a rubber rubbing surface, of channel shaped clips engaging portions of the frame and having hook shaped flanges which grip edge portions of the rubber to hold the same in position. 5. In a washboard, the combination with a frame including a backboard, a rubber rubbing surface fitting against the backboard, and channel shaped clips embracing edge portions of the backboard and rubbing surface to anchor the rubbing surface to the frame. 6. In a washboard, the combination with a frame including a backboard and grooved members receiving edges of the backboard, a rubber rubbing surface fitted against the backboard, and clip members having gripping elements engaging the rubber rubbing surface and portions fitting in the grooves and held in position therein by the backboard. 7. In a washboard, the combination with a frame including a backboard and grooved members receiving edges of the backboard, a rubber rubbing surface fitted against the backboard, and channel shaped clips embracing edge portions of the backboard and rubbing surface and held in position by engagement with the walls of the grooves. 8. In a washboard, the combination with a frame including a backboard and grooved members receiving edges of the backboard, a rubber rubbing surface fitted against the backboard, and channel shaped clips embracing edge portions of the backboard and rubbing surface, said clips being clamped in position between the backboard and walls of the grooves and being formed with jaw portions which grip the rubbing surface to hold the same in position. 9. In a washboard, the combination with a frame including a backboard and grooved members receiving edges of the backboard, a rubber rubbing surface fitted against the backboard, and metal clips fitted upon edge portions of the backboard and received within the grooves of the frame, said clips comprising jaw portions which engage the rubbing surface to hold the latter in position. 10. In a washboard, the combination of a frame, a rubbing surface, and metal clips carried by the frame and having portions gripping the rubbing surface to hold the latter in position. 11. In a washboard, the combination of a support comprising a plurality of grooved retaining members, a rubber rubbing surface formed with projecting portions, and metal clips having portions which are entered in the grooves of the retaining members and also having hooked portions which engage and grip projecting portions of the rubbing surface to hold the latter in position.

In testimony whereof I affix my signature.

NEIL D. LENNER.
